UNITED STATES PATENT OFFICE

GENE GOTT, OF KANSAS CITY, MISSOURI

DESIGN FOR A NOVELTY TOY

Application filed February 27, 1932. Serial No. 43,026. Term of patent 3½ years.

To all whom it may concern:

Be it known that I, GENE GOTT, a citizen of the United States, residing at Kansas City, in the county of Jackson and State of Missouri, have invented a new, original, and ornamental Design for a Novelty Toy, of which the following is a specification, reference being had to the accompanying drawing forming part thereof, in which:

The figure is a perspective view of a novelty toy, showing my new design.

I claim.

The ornamental design for a novelty toy, as shown.

GENE GOTT.
